UNITED STATES PATENT OFFICE.

JOHN C. GOAR, OF JAMAICA PLAIN, MASSACHUSETTS.

IMPROVEMENT IN BELT-SHIPPERS.

Specification forming part of Letters Patent No. 36,707, dated October 21, 1862.

To all whom it may concern:

Be it known that I, JOHN C. GOAR, of Jamaica Plain, in the county of Norfolk and State of Massachusetts, have invented a new and useful Improvement in Belt-Shippers; and I do hereby declare that the following is a full, clear, and exact description of the same, reference being had to the accompanying drawing, forming part of this specification, said drawing representing a front view of a belt-shipper with my improvement.

This invention consists in a certain novel arrangement of an oscillating double elbow-piece and a single spring locking-pawl, in combination with a two-notched shipping-slide, which carries the belt-guide, and with a lever or its equivalent, whereby, when the slide has been locked by the pawl with the guide in either of its two positions for guiding the belt the pressure applied to the lever or its equivalent to shift the slide for shipping the belt will first cause the elbow-lever to disengage the pawl from one notch of and so unlock the slide, and then give the latter the proper movement, and that when, after the movement of the slide has been given, the pawl is allowed to enter the other notch of and so lock the slide until the pressure on the lever is reversed.

To enable others skilled in the art to make and apply my invention, I will proceed to describe its construction and operation.

A represents a board or plate or any fixed support which carries all the parts of the shipper.

B B' are guides attached to the support A for the reception of the horizontally-moving slide C, to which are rigidly attached the two horns a a', which constitute the belt-guide. At the middle of the length of the guide, and near the lower end thereof, the oscillating double elbow-piece D is attached to it by the pin b, upon which the said piece oscillates. In the lower edge of the slide, near the ends of the two lower arms, d d', of the double elbow-piece, are two square notches, c c', for the reception of the square-pointed tooth e of the locking-pawl E, which is attached by a pivot, f, to a plate, F, screwed to the support A, and which is constantly pressed upward by a spring, g, attached to the said plate below it, and on opposite sides of the upper arm, d', of the double elbow-piece there are attached to the slide two stops, h h',

to limit the oscillating movement of the said piece. The pawl E is thick enough for the tooth e to project from the notches c c' under the bottom of the double elbow-piece D. The guides B B' are arranged to serve as stops to the horns a a', for the purpose of limiting the horizontal movement of the slide, so that such movement may only be sufficient to ship the belt.

G is the lever operated by hand to shift the slide, pivoted by a fulcrum-pin, j, to the support A, and connected by a rod, H, with a stud, d', secured in the upper arm, d', of the double elbow-piece D.

The operation of the shipper is as follows: The drawing represents the slide and attached belt-guide a a' as having been shifted to the right and the slide as locked by the tooth e of the pawl entering the notch c. To shift it to the left, the lever is to be moved in that direction. The first part of this movement of the lever is caused by the action of the rod H on the upper arm, d', of the oscillating double elbow-piece D, to produce the depression of the arm d of the said piece upon the tooth e of the pawl E, and so to disengage the said pawl from the slide C and unlock the latter, and by the upper arm, d', of the said piece E coming in contact with the stop h the continued movement of the lever is caused to move the slide to the left until the horn a comes in contact with the guide B and prevents the further movement of the slide, when the notch c', having arrived over the tooth e of the pawl, the spring g, by its upward pressure on the pawl, causes its tooth e to enter the said notch and lock the slide. To return the slide and its attached belt-guide to the position shown in the drawing, the lever is moved to the left, and in such movement it carries the upper arm, d', of the piece D with it as far as the stop h', and so causes the arm d' of the said piece to depress the pawl E, and so unlock the slide and bring the arm d' against the stop h', after which the continued movement of the lever causes the slide to move to the position shown, when, the horn a' of the belt-guide coming in contact with the guide B', the slide is stopped with the notch c over the tooth e of the pawl, and the spring g, by its upward pressure on the pawl, causes the tooth to enter the notch c and lock the slide.

Instead of the lever G and rod H, there may be used as their equivalent two cords attached to the arm d^2 of the elbow-piece D, and passing over pulleys arranged in the guides B B' and hanging down to convenient positions, as shown in red outline in the drawing. By pulling the right-hand cord the same effect is produced as by moving the lever to the right, and by pulling the left-hand cord the same effect is produced as by moving the lever to the left.

What I claim as my invention, and desire to secure by Letters Patent, is—

The combination, with the belt-slide C and the spring locking-pawl E, of the double-acting detacher and slide-mover D, in the manner herein shown and described.

JOHN C. GOAR.
